(57) **CLAIM**

The ornamental design for a valve handle, as shown and described.

DESCRIPTION

FIG. 1 is a front perspective view showing my new design for a valve handle, the portion shown in dotted lines is for illustrative purposes only and forms no part of the design, FIG. 2 is a rear perspective view thereof, the portion shown in dotted lines is for illustrative purposes only and forms no part of the design,

FIG. 3 is another rear perspective view of the valve handle at a slightly shifted angle from FIG. 1, the portion shown in dotted lines is for illustrative purposes only and forms no part of the design,

FIG. 4 is an enlarged plan view thereof, the portion shown in dotted lines is for illustrative purposes only and forms no part of the design,

FIG. 5 is a front perspective view of an alternate positioning of the valve handle, the portion shown in dotted lines is for illustrative purposes only and forms no part of the design,

FIG. 6 is a rear perspective view thereof, the portion shown in dotted lines is for illustrative purposes only and forms no part of the design,

FIG. 7 is another front perspective view of the valve handle at a slightly shifted angle from FIG. 5, the portion shown in dotted lines is for illustrative purposes only and forms no part of the design,

FIG. 8 is an enlarged bottom view, the portion shown in dotted lines is for illustrative purposes only and forms no part of the design; and,

FIG. 9 is a rear view thereof, the portion shown in dotted lines is for illustrative purposes only and forms no part of the design.
